UNITED STATES PATENT OFFICE.

ARTHUR COHN, OF NEUKÖLLN, NEAR BERLIN, GERMANY.

PROCESS FOR THE MANUFACTURE OF LACQUERS AND VARNISHES.

1,080,100.

Specification of Letters Patent.

Patented Dec. 2, 1913.

No Drawing.

Application filed April 17, 1912. Serial No. 691,512.

To all whom it may concern:

Be it known that I, ARTHUR COHN, a subject of the King of Prussia, residing at Neukölln, near Berlin, in the Kingdom of Prussia, Germany, have invented a new and useful Improved Process for the Manufacture of Lacquers and Varnishes, of which the following is a specification.

Chinese wood oil dries more quickly and produces a harder surface than other drying oils, but it has not been possible hitherto to utilize it as a satisfactory varnish or lacquer, whether thickened or not and whether combined with driers or not, because it is very liable to dry with a dead or reticulated surface, particularly noticeable, for instance, under gas light. A mixture of wood oil with ethereal oils such as rectified turpentine oil, pine oil, etc., or with volatile substances of inorganic nature such as benzol, benzin, etc., does not produce a reliable lustrous film. For these reasons wood oil has been capable of use hitherto only in combination with large quantities of solid or solidifying substances such as resins, fatty oils, oil acids. Wood oil lacquer made with resins becomes brittle too soon, while wood oil in combination with fatty oils such as linseed oil dries much more slowly and softer than pure wood oil. Thus these additions do not allow the exceedingly good qualities of wood oil to appear except to a very limited degree.

The present invention is an improved process whereby wood oil can be made into lacquers or varnishes which dry quickly

with a lustrous surface and hard elastic texture, irrespective of the climate, light or temperature, with the use of only a small percentage of a suitable drier and without the necessity of any addition to the wood oil of other fatty oils, resins and the like, such as have heretofore been used. This object is effected by adding to the wood oil, in addition to any desired driers, terpenes and terpene turpentine oil, pine oil and the like, which are ordinarily used in the manufacture of lacquer and which have an average boiling point of from 153° to 162° C. give little or no help in remedying satisfactorily the above stated drawback. An entirely different product and an improved effect are obtained by adding to the wood oil, instead of the oils ordinarily used, terpenes, such as terpene oil, terpineol, and the like, preferably having a minimum boiling point of about 170° C.

I claim:

1. The herein described process of manufacturing lacquers and varnishes from wood oil, which consists in mixing the wood oil with a terpenylic substance having a minimum boiling point of about 170° C.

2. The herein described process of manufacturing lacquers and varnishes from wood oil, which consists in mixing the wood oil with a terpenylic substance.

ARTHUR COHN.
